UNITED STATES PATENT OFFICE.

HENRY CLAY ARMSTRONG, OF ASHLAND, WISCONSIN.

IRONING BOARD.

Application filed September 12, 1922. Serial No. 587,771.

To all whom it may concern:

Be it known that I, HENRY C. ARMSTRONG, a citizen of the United States, and a resident of Ashland, in the county of Ashland and State of Wisconsin, have invented a new and Improved Ironing Board, of which the following is a full, clear, and exact description.

This invention relates to ironing board structures, and more particularly aims to provide a self-contained collapsible supporting structure for the ironing board and a complementary ironing board therefor, characterized by marked simplicity, economy of manufacture, lightness of weight, and ease and rapidity of manipulation to change the same from collapsed to extended or working condition and vice versa.

One of the principal objects of the invention is to provide such a structure which, when extended ready for use, is firmly and strongly established and of absolute rigidity, due in part to the provision of simple auxiliary members which in addition to giving rigidity to the structure serve a useful purpose during the ironing process, as hereinafter set forth.

A further object of the invention is to provide a structure, not only of the kind above described, but also one so designed that the complete structure is a floor-supported one at all times; adapted, on the other hand, for complete collapse into what may be termed a panel-like, or substantially flat and thin, upright wall member to rest or lean against a room wall of the laundry; and constructed and arranged, on the other hand, so as to present no difficulty whatsoever in collapsing or extending the supporting parts for directly carrying the ironing board on their tops.

With such objects and others in view, the invention consists in the arrangement, relation and combination of parts below illustratively described, and particularly as claimed; and while, of course, the invention is not restricted to the precise details of construction disclosed or suggested herein, yet for the purpose of fully and clearly explaining the same, and by the illustrative description of a preferred embodiment thereof, reference is now had to the accompanying drawings.

In these drawings, in which like reference characters designate the same parts in the several views—

Figure 1 is a perspective view, showing the complete structure in extended and locked condition ready for ironing;

Fig. 2 is a bottom plan view of the ironing board;

Fig. 3 is a section on line 3—3 of Fig. 2;

Fig. 4 is a transverse vertical section taken on the line 4—4 of Fig. 1;

Fig. 5 is a front elevation of the structure completely collapsed; and

Fig. 6 is a transverse vertical section taken on line 6—6 of Fig. 5.

A pair of side-frames or gates 7, here preferably of skeleton construction as shown, are hinged, as indicated at 8 in Fig. 5, to a back-frame or main member 9, adapted to be disposed at all times with its back flat against or close to a wall of the laundry. Thus the foot-portions 10 of the back-frame are adapted at all times to rest over fixed spots on the laundry floor. These foot-portions 10, together with foot-portions 11, one dependent from each of the side-frames 7 at points removed from the pivotal axes of the side-frame, constitute what may be termed four table legs, permitting the structure, when fully extended as shown in Fig. 1, to rest squarely and solidly on the floor.

Back-frame 9, here also preferably of skeleton construction, includes, as best shown in Figs. 1 and 4, a pair of end uprights 12 integral with foot-portions 10. These uprights preferably are tied together at three points, first, at their tops, by a horizontal rod 13, second, at their middles, by a horizontal slat 14, and third, near their bottoms, by a horizontal slat 15. The slats 14 and 15, as clearly shown in the drawings, are the parts of the back-frame 9 to which the side-frames 7 are hinged at 8 as above described.

While the provision of these slats 14 and 15 serves, in combination with the rod 13, to make the back-frame very rigid with a minimum of structural material, the presence of the slats at the points specified, and with each slat of less thickness than the width of an upright 9 as shown, also permits the hinging of the side-frames 7 to be

so located, as will be noted particularly from Fig. 6, that on collapsing the side-frames, the latter will swing in parallel with the slats so that the outer faces of the side-frames lie flush with the front edges of the uprights 9.

The rod 13, in addition to acting as a rigidifying agent, serves the further useful purpose of providing an ideally located hanger over which may be folded or draped the ironed articles as they are completed one by one.

An ironing board 16 is adapted to rest directly and squarely on the tops of side-frames 7, as shown best in Figure 1; each side-frame at its top carrying a projection 17, with which projections are engaged a pair of recesses 18 in the underside of the board when the board is set in position. The underside of the board may be further provided with longitudinal grooves 19 to minimize warping. The board is preferably tapered at one end and this tapered end preferably overlies the side-frame to the left of Fig. 1 as shown, and then the side-frame last mentioned is preferably cut away, as indicated at 20, to provide an unobstructed space around and below the front and back edges of the tapered end of the board, to facilitate the ironing and handling of belted portions of articles being ironed.

The board 16 may carry a plurality of sets of recesses similar to the recesses 18, for engaging the projections 17 on side-frames 7, and to permit various adjustments of the board on the side-frames. A single additional pair of such recesses for example, is shown at 21. Of course, the board may be made of a length exceeding the width of back-frame 9 to an extent even greater than that indicated, if many pairs of recesses similar to recesses 18 and 21 are present.

The side-frame 7 to the right of Figure 1 is further connected to the upper slat 14 of back-frame 9, by means of a bracing means as indicated at 23, which may conveniently consist, as indicated, of a snap-link quick-collapsible brace of the familiar type. It will be seen that the presence of such a brace, even in the structure as so far described, that is, comprising merely a back-frame, the two side-frames hinged thereto as gates, and the ironing board overlying the tops of such gates, serves to hold the back-frame and at least one side-frame against relative movement, and so maintains the whole structure squarely on the floor, for a variety of useful purposes, such, for instance, as to facilitate lifting the tapered end of the board to slip a skirt or other tubular garment over and onto the board, to facilitate correct initial mounting of the board on the two side-frames in setting up the structure for ironing, to facilitate collapsing the side-frames, one after

the other against the back-frame after removing the ironing board upon completing the ironing, etc.

In combination with the elements so far described, the complete structure preferably includes certain auxiliary elements which are not only adapted to give additional rigidity to the entire structure when the parts are extended to support the ironing board 16 in position for ironing, but which are also of immediate usefulness in themselves.

These auxiliary elements include diagonal braces 24 on the rear of back-frame 9, between uprights 12 and slats 14 and 15, and a third swinging frame or shelf member 25, hingedly connected to lower slat 15 at 22, as shown in Figure 4.

This auxiliary swinging frame or shelf member 25 with the structure extended, ready for ironing, constitutes a true shelf in a position which is out of the way of the worker at the ironing board and is yet so located as to intercept the lower portions of sheets and similar large articles being ironed and thus prevent such articles from dropping to and being soiled on the floor.

The useful purpose of the diagonal braces 24, in addition to their function further to rigidify the back-frame 9, and the entire structure, will be described immediately below in connection with a particular reference to Figs. 5 and 6 showing the entire structure in completely collapsed condition.

Referring now particularly to said Figs. 5 and 6, and in order to describe the manner in which all the various parts of the entire structure are compactly collapsed into a panel-like, substantially flat and thin, upright wall member to rest or lean against a room wall of the laundry, and with the main or back-frame 9 overlying precisely the same area of the floor as when all parts were extended as in Fig. 1 for ironing, attention is directed first to the provision on back-frame 9 of a plurality of hook-shaped devices 27 anchored in uprights 12, the upper ones of which may be turned as shown in broken lines in Fig. 6; and to a projection 30 on the side-frame 7 to the right of Fig. 5, and a recess 31 in the board 16 as shown in Fig. 2, said projection and recess to interlock when the parts are collapsed as shown in Fig. 6 and as hereinafter described.

It will be seen from Figs. 5 and 6 that the board as finally collapsed is only as thick at any point as the width of an upright 12, plus the thickness of board 16; and that the various hingedly connected parts are folded in toward back-frame 9 in a certain order facilitating a quick and convenient series of collapsing operations. Thus, in collapsing the structure, the first step, after removing the board from the tops of side-

frames 7, is to lift shelf 25 until the same is disposed vertically above slat 15 and flush with such slat. As the shelf is performing its upward swing toward the position last mentioned, the side-frame 7 to the left of Fig. 1 is swung in to lie close against and to overlap the up-swung shelf. The shelf and the side-frame last mentioned will now have no tendency to drop away from their collapsed positions, as the shelf is squarely above bottom slat 15, and the in-swung side-frame has its foot-portion 11 in slight frictional contact with the floor. Next, the brace 23 is struck in at its center where its two link members are pivotally connected, and the side-frame 7 to the right of Fig. 1 is swung in parallel and flush with the other side-frame previously swung in. Finally, upper devices 27 having been 20 turned as indicated in dotted lines in Fig. 6, board 16 is arranged on lower device 27 to cause projection 30 to engage recess 31; whereupon upper devices 27 are downturned to lock the board in position. It 25 will further be seen that back-frame 9, as here preferably constructed, may be described as a shallow box-like or crate-like structure, resting on its own foundation at all times, directly on the floor; and by its 30 box-like nature, being adapted to completely house all swinging parts of the structure when the structure is to be collapsed.

The diagonal braces 24 have considerable usefulness in the structure as collapsed, as 35 they cooperate directly with the ironing board (when mounted in the devices 27) to positively hold the in-swung elements in collapsed condition as described, avoiding any undue strains on the hinges which 40 mount shelf 25 on bottom slat 15 of back-frame 9.

As here shown, upper slat 14 of back-frame 9 is provided with a cut-out portion 45 as indicated at 28, to provide a handle 29 which may be convenient in shifting the structure in the laundry whenever deemed desirable.

It will be seen that an exceedingly sturdy and rigid, yet simple and light structure is 50 provided, and one having the outstanding advantage, among the others hereinabove mentioned, of being adapted to be collapsed into very small compass, with the collapsing and extending operations of maximum ease and quickness; and at all times the back-frame, which means the entire structure when collapsed, may remain in a fixed position close against a wall of the laundry.

I claim:

60 1. An improved ironing board structure including, in combination, a back-frame to rest on the floor, a pair of gates hingedly connected thereto and lying wholly to one side of the back-frame and adapted to be

folded back close against the back-frame, 65 said gates having floor contacting foot-portions when swung to extend angularly away from the back-frame and substantially parallel to each other, an ironing board adapted to rest on the tops of the gates when 70 thus extended, and supporting means for the ironing board mounted on the back-frame and adapted to receive the iron board after the gates are folded back against the back-frame, such supporting means being adapted 75 to hold the ironing board parallel with the back-frame and with the folded back gates to retain the latter collapsed against the back-frame; substantially as described.

2. In an ironing board structure, the combination of hingedly connected back and side-frames all having floor contacting portions whereby the side-frames may be extended in substantially parallel relation away from the back-frame, an ironing board adapted 80 to rest on the side-frames when the latter are extended, quick detachable means carried by the ironing board and the side-frame for locking the parts in ironing position, and an auxiliary bracing means between one 85 side-frame and the back-frame, the other side-frame having an upstanding part at a point removed from the back-frame for solely supporting the overlying end of the ironing board, whereby that end of the ironing board may be used conveniently for ironing bellied parts of articles to be ironed and may be lifted from over its underlying side-frame without causing relative movement between the other side-frame and the 90 back-frame and to permit a skirt or similar tubular article to be slipped over and on to the ironing board; substantially as described.

3. In an ironing board structure, the combination of a back-frame and a pair of side-frames, each of the side-frames being hinged along one vertical edge to the back-frame near a vertical edge of the latter, and such side-frames being of such widths that 105 they are also adapted to be folded in toward each other to lie parallel against the back-frame, a self member hingedly connected to the back-frame intermediate the tops and bottoms of the side-frames and between the 110 hinged connections of the side-frames to the back-frame, such hinged connections being so located that the shelf member and the side frames may be folded back against the back-frame in overlapping relation, and supporting devices carried by the back-frame and adapted to receive the ironing board and retain the latter with its flat vertical and overlying the folded-in shelf member and side-frames; substantially as 115 described.

HENRY CLAY ARMSTRONG.
